(57) **CLAIM**

The ornamental design for display device, as shown and described.

DESCRIPTION

FIG. 1 is a front perspective view of the display device in a rolled state showing our new design according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the area within the dot-dash line with the reference numeral “8” in FIG. 1;

FIG. 9 is an enlarged view of the area within the dot-dash line with the reference numeral “9” in FIG. 6;

FIG. 10 is a front perspective view of the display device according to the first embodiment in a flat state;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is an enlarged view of the area within the dot-dash line with the reference numeral “17” in FIG. 10; and,

FIG. 18 is an enlarged view of the area within the dot-dash line with the reference numeral “18” in FIG. 15.

The broken lines indicate unclaimed portions of the article that form no part of the claimed design.

The dot-dash-dot broken lines indicate where the enlargements have been taken and form no part of the claimed design.

1 Claim, 13 Drawing Sheets
